UNITED STATES PATENT OFFICE.

LAWRENCE F. RYAN, OF YONKERS, NEW YORK.

GAME DEVICE.

1,402,799.

Specification of Letters Patent. Patented Jan. 10, 1922.

Application filed August 18, 1919. Serial No. 318,412.

To all whom it may concern:

Be it known that I, LAWRENCE F. RYAN, a citizen of the United States, residing at Yonkers, in the county of Westchester and 5 State of New York, has invented certain new and useful Improvements in Game Devices, of which the following is a specification.

This invention relates to improvements 10 in game devices and has for its object to provide a ball bat having means whereby it may be attached to the hand.

Another object of the invention is to provide a ball bat approximately the shape 15 of a person's hand and means whereby it may be attached to the hand.

Still another object of the invention is 20 to provide a bat approximately the shape of a person's hand and means whereby it may be attached to either the right or left hand and conform to the shape of either.

Still another object of the invention is 25 to provide a bat having a flexible piece for attaching the bat to a wearer's hand said piece having a thumb opening and means whereby said opening may be made to suit the thumb of either the right or left hand.

With the above and other objects in view, 30 I have invented the device illustrated in the accompanying drawings in which:—

Figure 1 is a top plan view of my device shown fixed to a hand, the hand being in dotted lines.

35 Figure 2 is a plan view of the reverse side of the device the fastening strap being reversed thereon in dotted lines, and,

Figure 3 is a detail plan view of the fastening member removed from the bat.

40 Like reference characters indicate like parts throughout the specification and in the several views in the drawings in which 1 indicates a board the contour shape of a person's hand without the thumb. This 45 board may be made of any suitable material such as wood, metal, papier maché, or the like, and is reversible so that it may be applied to either the right or left hand. To the edge 2 opposite the thumb edge 3 of the 50 board and near the end 4 adjacent the wrist portion of the board is hingedly secured at 6 a flexible strap 5 adapted to fit over the wrist and back of a person's hand. The other end of this strap is bifurcated to provide a thumb opening 7, whereby a person 55 will have free use of the thumb in using

the device, the extremities 8 and 9 are provided with eyes 10 and 11 which are adapted to engage the hooks or pins 12 and 13 one of which is on the edge 3 near the center 60 of the board, the other pin 13 being on the angularly disposed edge 14 whereby said extremities when fastened have a tendency to pull against one another and hold the device more securely to the hand. It is 65 not essential for the strap to fit tightly around the wrist as a slight pressure of the fingers upon the board or bending of the band will cause the strap to press tightly against the back of the hand, thus the device 70 will easily fit to hands of various sizes. The device is especially adapted for batting balls back and forth. As there are many other uses to which the invention is readily adaptable I do not limit its uses to that of a bat. 75

The strap 5 may be formed of leather, canvas or any other suitable material and it may also have inset 15 of elastic material if desired in order to more readily accommodate to hands of various sizes. 80

Now having described my invention that which I claim to be new and desire to procure by Letters Patent is:—

1. In a device of the character described a base and a hand strap having one end secured to one edge of the base and means for fastening the other end of the strap to another edge of the base, said strap being reversible upon the base, whereby the base may be secured to either hand of a user, 90 said strap having a thumb opening. 85

2. In a device of the character described a base and a hand strap having one end secured to one edge of the base and means for fastening the other end of the strap to 95 another edge of the base, said strap being reversible upon the base, whereby the base may be secured to either hand of a user, said strap having a thumb opening, arranged to receive the thumb of either the 100 right or left hand.

3. In a device of the character described a base and a hand strap having one end secured to one edge of the base and means for fastening the other end of the strap to 105 another edge of the base, said strap being reversible upon the base, whereby the base may be secured to either hand of a user, said strap having a thumb opening, arranged to receive the thumb of either the 110 right or left hand, said base being shaped to a hand.

4. In a device of the character described a base and a hand strap having one end secured to one edge of the base and means for fastening the other end of the strap to another edge of the base, said strap being reversible upon the base, whereby the base may be secured to either hand of a user, said strap having a thumb opening, arranged to receive the thumb of either the

right or left hand, said base being shaped 16 to a hand, said base being rigid.

In testimony whereof I affix my signature in presence of two witnesses.

LAWRENCE F. RYAN.
